UNITED STATES PATENT OFFICE.

FRANKLIN J. HOFF, OF YOUNGSTOWN, OHIO.

VEHICLE-SIGNAL.

1,290,993.

Specification of Letters Patent. Patented Jan. 14, 1919.

Application filed April 6, 1918. Serial No. 227,036.

To all whom it may concern:

Be it known that I, FRANKLIN J. HOFF, a citizen of the United States, and a resident of Youngstown, in the county of Mahoning and State of Ohio, have invented certain new and useful Improvements in Vehicle-Signals, of which the following is a specification.

This invention relates to a signal or direction indicator particularly adapted for use upon automobiles and the primary object of the invention is to provide a signal which is carried at the rear end of the vehicle and will attract the attention of the driver of a car or vehicle in the rear of the same, upon its operation, indicating the direction to be taken by the vehicle upon which it is mounted.

A further object of this invention is to provide a vehicle signal, including a pivotally mounted plate having arrow shaped openings cut therein, and a shutter plate both of which are operated by the longitudinal movement of an operating rod for exposing one of the arrows and moving the shutter plate and the arrow carrying plate upon movement of the operating rod to its normal position to hide the arrow opening from view and also render relatively invisible a sign such as "Slow down" which sign is exhibited during the exhibiting of one of the arrow openings.

A further object of the invention is to mount a translucent plate inwardly of the arrow openings and the sign, and to provide a housing or casing of dark color so that when the shutter and arrow carrying plate are moved for exhibiting one of the arrows and the sign, both the arrow opening and the sign will stand out clearly.

A further object of the invention is to provide a tail light for the vehicle which is carried by the indicator or signal structure and a portion of the lens of which is shaded when the arrow is exposed for detracting from the brilliance of the tail light and preventing it from blurring the arrow indication.

Other objects of the invention will appear in the following detailed description, taken in connection with the accompanying drawings, forming a part of this specification and in which drawings:

Figure 1 is a view showing the application of the signal to a motor vehicle.

Fig. 2 is an elevation of the signal.

Fig. 3 is a fragmentary elevation of the signal showing one of the arrows in an exposed position.

Fig. 4 is a section through the signal structure illustrating the shutter and arrow carrying plate and the mechanism for operating the same, and further taken on the line 4-4 of Fig. 5.

Fig. 5 is a vertical section through the indicator taken on the line 5-5 of Fig. 4.

Fig. 6 is a detail perspective view of the operating lever of the indicator.

Fig. 7 is an elevation of the arrow carrying plate.

Referring more particularly to the drawings, A indicates a motor vehicle of the pleasure type, which carries the signal B at the rear end of the same. The operating lever and its companion mechanism C are carried by the vehicle in close proximity to the controlling levers of the same and where it can be conveniently reached by the driver of the machine.

The signal mechanism B comprises a housing 1 the rear side 2 of which is removable, to permit access to the interior thereof. The front 3 of the housing 1 is provided with an elongated opening 4 the end portions of which are enlarged as shown at 5. The words "Slow down" are cut in the front side 3 above the opening 4, and a circular opening 6 is formed in the housing below the rectangular opening 4. A red glass lens 7 is positioned in the opening 6 and this lens, co-acting with the light bulb 8 forms a tail light for the vehicle.

The front side 3 is provided with a second elongated opening at the lower edge of the same along the ends and lower side of which are positioned guiding and supporting flanges 8 which carry a plate 9 in which is perforated the license number of the vehicle. A white translucent plate 10 is positioned within the housing behind the plate 9 to enhance the visibility of the license numbers and letters.

A plate 11 of white translucent material is supported by a suitable bracket structure 12 within the housing inwardly of the opening 4 and the words which are cut in the front side of the housing above the opening 4.

A plate 12 is pivotally mounted within the housing intermediate its ends as shown at 13. The lower edges of the plate 12 converge as they extend downwardly and this

plate is provided with an oval opening 14 which alines with the opening 6, and also with an opening 15 cut therein which is the shape of crossed arrows having their heads 5 pointing in opposite directions. An arm 16 is pivotally connected as shown at 17 to one lower edge of the plate 12 near one end thereof and to an operating rod 18 as shown at 19. The operating rod 18 is slidably supported by suitable bearings 20 which are in turn supported by a bracket structure 21 and when the operating rod 18 is moved longitudinally, in one direction it will move one of the arrows of the crossed arrow opening 15 10 into alinement with the opening 4, as clearly shown in Fig. 3 of the drawings, allowing the white translucent plate 11 to be exposed through the opening 4 and the arrow opening 15, causing a white arrow to be exhibited, the head of which points in the direction 15 to be taken by the vehicle.

A shutter plate 20 is slidably mounted within the housing 1 and it is provided with an elongated opening 22 shaped identical 25 with the opening 4, and providing an upper portion 23 and a lower portion 24. The upper portion 23, when the rod 18 is in its normal position is positioned directly behind the words "Slow down," cutting off the exhibiting of the translucent panel 11 through 30 the letters of this word while the lower portion 24 is positioned behind the opening 4, cutting off the exhibiting of the white translucent plate through this opening. An arm 35 25 is pivotally mounted within the housing 1 and it comprises arms 26 and 27, the former of which is connected to the shutter plate 22 near its terminal by suitable pins 28, for moving the shutter plate vertically upon 40 the rocking movement of the lever. The arm 27 of the lever 25 carries a pin 30 which rides over the edges and apex of a substantially triangularly shaped plate 31 which is carried by the operating rod 18. The pin 30 45 engaging the edges of the triangular plate 31 rocks the lever 25 upon longitudinal movement of the operating rod 18 for shifting the position of the shutters 22 and permitting or cutting off the exhibition of the 50 translucent plate 11 through the various openings in the front side 3 of the housing.

The shutter 22 is provided with a cut-out portion 32 extending upwardly from its lower end, and registering with the oval opening 14 and the lens opening 6 to permit 55 the rays from the lamp 8 to pass through the entire lens when the shutter is forming a closure for the opening 4. When the shutter 22 is lowered, at which time the plate 12 is 60 rocked to move one of the crossed arrows into alinement with the opening 4, the shutter forms a closure or curtain for the upper head of the opening 6, cutting off a part of the tail light and preventing the rays from 65 the light through the lens 7 from blurring

or interfering with the visibility of the arrow opening and also detracting the attention of a person in the rear of the car from the tail light to the arrow opening. The rays from the lamp 8, will, when this lamp 70 is lighted pass through the translucent plate 11 and further enhance the visibility of the arrow and the words "Slow down."

The rod 18 is connected to an operating lever 33, intermediate the ends of the lever. 75 The lever 33 is pivotally connected at its lower end, to a bracket 34 which may be carried by the vehicle body in close proximity to the driver's seat, so that the driver or operator of the vehicle may conveniently 80 reach and operate the lever 33. The lever 33 is mounted to be swung in either direction, from its normal vertical position for operating the rod 18 in either direction, depending upon the direction to be taken by 85 the vehicle, for moving the arrow openings into alinement with the opening 4 causing the arrow which points toward the direction to be taken by the vehicle to be exposed behind the opening 4. For example; when the 90 vehicle carrying the improved signal is going to turn to the left, the lever 33 is operated for moving the operating rod 18 and projecting the arrow opening 15^a behind the opening 4, as shown in Fig. 3 of the draw- 95 ings, and when the vehicle desires to turn to the right, the lever 33 is operated in the opposite direction, which will rock the plate 12 to move the other of the arrows into alinement with the opening 4.

Spiral springs 36 and 37 are connected to the lever 33 and to arms 38 carried by the bracket 34. The springs 36 and 27 return the lever 33 to its normal vertical position, after it has been operated and a spiral 105 spring 39 is coiled about the rod 18, forming a protection for the flexible portion 40 of this rod. A plate 41 is carried by the lever 33 and engages behind the bracket 34, acting as a guard and guide for the movement of 110 the lever.

The lamp 8 derives its power from the battery D of the vehicle or from any desired source, this invention not being restricted to the use of an electric lamp.

What is claimed is:

1. In a vehicle signal, the combination with a housing having an elongated exhibiting opening and a plurality of openings above said exhibiting opening and shaped to 120 form words, of a plate pivotally mounted within said housing and carrying crossed indications, means for rocking said plate to move one of said indications in registration with said elongated opening, and means 125 closing said exhibiting openings when said arrow indications are out of registration with elongated opening.

2. In a vehicle signal, the combination, of a housing having an exhibiting opening, a 130

- plate pivotally mounted within said housing and provided with openings forming crossed arrows, means for operating said plate to move one of said arrow openings in registration with said exhibiting opening, a shutter for normally closing said exhibiting opening, and operating means for synchronously operating said plate and shutter to move the shutter from registration with said opening upon movement of the plate to move one of said arrow openings into registration with the exhibiting opening.
3. In a vehicle signal, the combination, of a housing having an exhibiting opening, a plate pivotally mounted within said housing and provided with openings forming crossed arrows, means for operating said plate to move one of said arrow openings in registration with said exhibiting opening, a shutter for normally closing said exhibiting opening, operating means for synchronously operating said plate and shutter to move the shutter from registration with said opening upon movement of the plate to move one of said arrow openings into registration with the exhibiting opening, and a white translucent plate positioned within said housing inwardly of said shutter and pivoted plate and adapted for exhibition through one of the openings in the pivoted plate and the exhibiting opening to enhance the visibility of the arrow shaped openings.
4. In a vehicle signal, the combination, of a housing having an exhibiting opening and a tail light opening, direction indicating means for registration with said exhibiting opening, a shutter for closing said exhibiting opening, said shutter closing a portion of said tail light opening when moved out of registration with said exhibiting opening, and means for synchronously operating said shutter and direction indicating means.
5. In a vehicle signal, the combination, of a housing having an exhibiting opening and a tail light opening, a plate pivotally mounted within said housing and provided with crossed arrow shaped openings, means for rocking said plate to move one, at a time, of said arrow shaped openings in registration with said exhibiting opening, a shutter for closing said exhibiting opening, and means for operating said shutter synchronously with the rocking of said plate to move said shutter out of registration with said exhibiting opening and into partial registration with said tail light opening.
6. In a vehicle signal, the combination, of a housing having an exhibiting opening and a tail light opening, a plate pivotally mounted within said housing and provided with crossed arrow shaped openings, means for rocking said plate to move one at a time of said arrow-shaped openings in registration with said exhibiting opening, a shutter for closing said exhibiting opening, means for operating said shutter synchronously with the rocking of said plate to move said shutter out of registration with said exhibiting opening and into partial registration with said tail light opening, a white translucent plate positioned within said housing inwardly of said exhibiting opening, said housing provided with a second exhibiting opening below said tail light opening, and guiding and supporting flanges extending partially about said second exhibiting opening.

FRANKLIN J. HOFF.
